UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

UNDERFRAME.

1,178,494.

Specification of Letters Patent. Patented Apr. 11, 1916.

Application filed June 25, 1914. Serial No. 847,207.

To all whom it may concern:

Be it known that I, CLAUS J. WERNER CLASEN, a citizen of the United States of America, and resident of Davenport, Scott 5 county, Iowa, have invented a certain new and useful Improvement in Underframes, of which the following is a specification.

My invention relates to metallic underframes for railway cars and is directed especially to steel underframes of unusual length wherein the longitudinal members, and particularly the center sill, can be made of such form and size to successfully sustain the vertical strains of the load imposed 10 upon it, are, owing to their extreme length, more or less easily deflected sidewise or laterally by the buffing and pulling shocks of train service.

The object of my invention is to provide 20 a construction whereby the center sill is not only strongly trussed against lateral deflection but wherein all the principal members of the underframe are thoroughly tied in a single unitary structure, insuring against 25 distortion and maintaining it in the general rectangular form against all ordinary service shocks and strains. This I accomplish by the mechanism shown in the accompanying drawings in which—

30 Figure 1 is a perspective view of approximately one half of an underframe, showing the preferred form of invention wherein the bow shaped truss members extend from bolster to bolster. Fig. 2 is a similar view of 35 a modified form, wherein the bow shaped truss members extend from end sill to end sill. Fig. 3 is a detail indicating that the truss members may be located on top of the cross bearers as shown sectioned in full 40 lines, or underneath as shown in dotted lines. Fig. 4 is a similar detail with the truss member passing through the web of the cross bearers.

Similar reference numerals refer to similar parts throughout the several views.

While I have shown only one end of an underframe it is to be understood that both ends are similarly constructed. The center sill 1, side sills 2, 2, end sill 3, bolster 4 and 50 cross bearers 5, 5, 5, are members common to underframes of this type and form no part of my present invention. They can be of any desired shape and construction.

I have chosen to show a center sill made 55 of a single I beam which is always to be

preferred to the double center sill provided sufficient stiffness and strength can be secured. In ordinary fifty ton capacity cars 40 feet or less in length center sills of adequate rigidity and strength are always 60 available, but for cars of unusual length such as the modern 50 ton capacity 50 ft. box cars, the sills are so long, that while sections of sufficient depth are available from which sills may be constructed of 65 sufficient strength and stiffness to properly sustain a vertical load, they are liable to be too weak and limber laterally to properly resist buffing shocks of train service.

My invention resides in providing means 70 for stiffening or trussing a single center sill (although it can be just as readily applied to a double center sill) against sidewise or lateral deflection. The preferred manner of accomplishing this is shown in Fig. 1 wherein the angles 6, 6 are extended from the body-bolster to body-bolster 4 with their ends securely riveted to the bolster on each side of and in close proximity to the center sill 1. These angles are gradually bowed 75 outwardly until they closely approach the side sills 2, 2 at the center of the underframe, from which point they again bow inwardly to the bolster at the other end of the underframe. They are securely riveted to each 80 cross bearer at the point of intersection therewith, thus forming the chords of a heavy powerful truss on each side of the sill, in which the cross bearers function as struts (it being understood that the cross bearers are all securely riveted to the center sill at the point of contact or intersection therewith). These truss chords may be made to extend from end sill to end sill as 85 shown in Fig. 2, or they may be made to bow inwardly toward the center sill as diagrammatically shown by the dotted lines 7, 7. Being rigidly secured to all the cross bearers with which they come in contact 90 they not only stiffen the center sill laterally but also immeasurably stiffen the entire underframe against distortion and especially against racking or going out of square from 95 poling strains or other service conditions.

It will be observed that the truss chords 100 are not directly connected to the side sills; in fact they would perform their function of preventing lateral buckling of the center sill in an underframe without side sills fully 105 as well as in an underframe with side sills.

As shown in, Figs. 3 and 4 these truss chords may be run above, below or through the web of the intersected members.

What I claim is—

5. 1. In an underframe for railway cars, the combination of end sills and side sills, a center sill extending from end sill to end sill, bolsters and cross bearers extending from side sill to side sill and secured to said center sill, bowshaped-buckling-resisting chords on each side and in the horizontal plane of said center sill extending from bolster to bolster and intersecting said cross bearers and secured thereto.
10. 2. In an underframe for cars, the combination of a center sill and bow shaped truss chords extending from end to end of said center sill on each side and in the horizontal plane thereof, and strut forming cross
- 15.

bearers secured to said truss chords and center sill, said chords being constructed of rolled flanged steel to resist lateral buckling of said center sill.

3. In an underframe for cars, the combination of center sill-lateral-buckling-resisting means comprising rolled flanged bow-shaped truss chords extending continuously from end to end of said center sill on each side and in the horizontal plane thereof, and a plurality of strut-forming cross bearers secured to said truss chords and center sill.

Signed by me at Davenport, Iowa, this 23rd day of June, 1914.

CLAUS J. WERNER CLASEN.
